DESIGN FOR A HANDLE FOR ELECTRIC IRON

John N. Polivka, Minneapolis, Minn., and Francesco Collura, New York, N. Y., assignors to General Mills, Inc., a corporation of Delaware

Application February 1, 1946, Serial No. 126,160

Term of patent 14 years

(Cl. D49—6)

To all whom it may concern:

Be it known that John N. Polivka and Francesco Collura, citizens of the United States and residents thereof, and of Minneapolis and New York, in the counties of Hennepin and New York and States of Minnesota and New York, respectively, have invented a new, original, and ornamental Design for a Handle for Electric Iron, of which the following is a specification, reference being had to the accompanying drawing, forming a part thereof.

Figure 1 is a top plan view of the handle for electric iron showing our new design;

Fig. 2 is a side elevation of same; and

Figs. 3 and 4 are front and rear elevations respectively.

We claim:

The ornamental design for a handle for electric iron, as shown.

JOHN N. POLIVKA.
FRANCESCO COLLURA.
